UNITED STATES PATENT OFFICE.

EDDIE P. TRUESDALE, OF CAMDEN, SOUTH CAROLINA.

SAFETY ATTACHMENT FOR RAZORS.

1,012,756.

Specification of Letters Patent. Patented Dec. 26, 1911.

Application filed April 6, 1911. Serial No. 619,415.

To all whom it may concern:

Be it known that I, EDDIE P. TRUESDALE, a citizen of the United States, residing at Camden, in the county of Kershaw and State 5 of South Carolina, have invented certain new and useful Improvements in Safety Attachments for Razors, of which the following is a specification.

This invention relates to safety attachments for razors, and has for its object to provide an attachment of simple structure which may be applied to razors irrespective of the breadth of their blades, and which when in position upon the razor blade has 15 a set of teeth disposed transversely of the cutting edge of the blade so that the blade may be used with safety.

With the above object in view the attachment includes two members which slidably 20 engage each other, means being provided upon one of the members for clamping the said members together in an adjusted position. Thus the members may be adjusted to the width of the blade of the razor to 25 which the attachment is applied. A set screw is threaded through the clamping device and is adapted to engage the side of the razor blade and hold the attachment in position upon the said blade.

30 For a full understanding of the invention reference is to be had to the following description and accompanying drawings, in which:

Figure 1 is a perspective view of the attachment applied to a razor; Fig. 2 is a transverse sectional view of the same; and Fig. 3 is a perspective view of the parts of the attachment disconnected.

Corresponding and like parts are referred 40 to in the following description and indicated in all the views of the accompanying drawings by the same reference characters.

The attachment consists of members 1 and 2. These members are preferably formed 45 from sheet metal, and the member 1 is provided at its back with a channel 3 which is adapted to receive the back of the razor blade. The member 1 is provided upon its top side with a ledge 4 having at its inner 50 and outer edges upstanding parallel flanges 5. A post 6 is mounted upon the ledge 4 midway between the flanges 5 and is both externally and internally threaded.

The member 2 is provided at its outer or 55 forward portion with a set of teeth 7 which are adapted to extend transversely across

the cutting edge of the razor blade. The said member 2 is also provided with a bracket portion 8 which lies upon the ledge 4 of the member 1 and fits snugly between 60 the flanges 5 thereof. The bracket portion 8 is provided with an elongated slot 9 which receives the post 6. The long dimension of the slot 9 is parallel with the flanges 5, so that the members 1 and 2 may be adjusted 65 laterally with relation to each other but are constrained against any independent longitudinal movement with respect to each other. A nut 10 is screw threaded upon the exterior of the post 6 and is adapted to bear 70 against the outer surface of the bracket portion 8, whereby the members 1 and 2 are held in adjusted positions with relation to each other. A set screw 11 engages the interior thread of the slot 9 and at its inner 75 end is adapted to bear against the side of the razor blade, indicated at 12, when the attachment is in position upon the blade. Therefore it will be seen that the members 80 1 and 2 may be adjusted to fit over razor 85 blades of different breadth, and when the set screw is forced against the razor blade, the strain upon the attachment will take place at the post 6 and the overlapping portions of the members 1 and 2, so that the said members will not bend or buckle in consequence of such strain.

Having thus described the invention, what I claim as new is:

1. A safety attachment for razors, comprising members adjustable laterally with relation to each other but constrained against independent longitudinal movement, said members having overlapping parts one of which is provided with a slot, 90 an externally and internally threaded post mounted upon the other overlapping part and passing through said slot, a clamp nut 95 screwed upon the exterior of the post, and a set screw threaded through the interior of 100 the post.

2. A safety attachment for razors, comprising a member having a channeled portion and provided with a laterally disposed ledge having at its inner and outer edges 105 parallel flanges, an externally and internally threaded post mounted upon the ledge, a second member provided at its outer portion with teeth adapted to lie transversely across the cutting edge of the razor blade, 110 said second member having a bracket portion provided with a slot, said bracket por-

tion lying upon the ledge portion of the first mentioned member and fitting snugly between the flanges thereof, the slot upon the bracket portion receiving said post, a nut 5 screw threaded upon the post and adapted to engage the bracket portion, and a set screw threaded through the post.

In testimony whereof, I affix my signature in presence of two witnesses.
